DOOR CLOSER

Lester C. Perkins, Spokane, Wash., assignor, by
direct and mesne assignments, to David J.
Bissell, Spokane, Wash.

Application September 17, 1934, Serial No. 744,378

2 Claims. (Cl. 16—70)

My present invention relates to improvements in door closers of the type employed to automatically close doors.

An important object of my invention is to provide a door closer which is adjustable to permit regulation of the closing pressures of the device.

A further object of my invention is to provide a device of the nature described which may be quickly and conveniently regulated and adjusted.

10 A still further object of my invention is the provision of a device so compact and simple of construction as to be both inexpensive in cost of manufacture and proficient in the performance of its functions.

15 Other objects and advantages will be apparent during the course of the following description.

In the accompanying drawings, forming a part of this specification and in which like numerals are employed to designate like parts throughout the same:

20 Figure 1 is a view in elevation of the closer device of my invention;

Figure 2 is a central horizontal longitudinal section through the same; and

25 Figure 3 is an enlarged detail of the air escape control of the device of my invention.

In the drawings, wherein, for the purpose of illustration, is shown the preferred embodiment of my invention, the numeral 5 designates the 30 base portion of the door closer which may be cast or otherwise formed. Integral with the base 5 and extending therefrom is a bracket 6 which is roughly U-shaped and has two circular yokes 7 and 7' that support the housing 10 between them. 35 At their outer ends the yokes are rigidly joined by the extension bracket 8 which forms a pivotal support for the operating lever 9.

The housing 10 is cylindrical in shape and is secured by means of rivets or screws through the 40 circular yokes 7, 7'. One end of the cylinder 10 is closed by the head 11 (to left in the drawings) and the other end by the air escape head 12. Head 11 is secured within the end of the cylinder 10 by means of guide rods 13, 13' threaded in the guide block 14 which is anchored at the approximate middle of the cylinder by screws through the cylinder wall. Head 12 is threaded into the opposite end of the cylinder.

45 Thus it will be apparent that two cylinders are formed on either side of a guide block 14, the one to the left housing the mechanical parts of my device and the cylinder on the right, the pneumatic mechanism. Mounted to reciprocate within the cylinder is a piston 15, of the leather or rubber cup type, rigidly secured to a piston

rod 16 operating through the guide block 14. At its opposite end piston rod 16 has secured thereto a spring retaining cup 17, into which spring 18 is seated. Spring 18 is seated in the head 11. The bolt-headed guide rods 13, 13' pass 5 through head 11, are encircled by spring 18, and pass through holes in the spring cup 17, alongside piston rod 16 to a point where they engage and are threaded into guide block 14.

The cylinder 10 on its horizontal axis is slotted 10 at 19 and 20 to allow for the insertion of the slotted fork end 21 of the operating lever 9 into the housing cylinder. A pin 22 through the slots in the fork of lever 9 attaches the lever to the piston rod 16. A pivot pin 23, through the offset 15 portion 9' of lever 9 secures and supports said lever upon bracket 8.

At its outer end lever 9 has a split head 9a which encircles and is tightened about ball 24 by means of a screw 25. Ball 24 supported from 20 the connecting lever 26 serves to form a semi-universal pivotal connection between lever 9 and lever 26. At its opposite end lever 26 is pivotally secured to anchor plate 27 by means of pin 28.

In head 12, an air escape port 29 allows for the 25 evacuation of air from the cylinder and for control of the escapement of air through port 29, I provide valve member 30 having a tapered end 31. Valve 30 is slidably operated in passage 32 which intersects port 29 and has at its lower end 30 valve seat 32'. Each end of valve 30 has attached thereto cords or wires 33, 33' which pass outwardly through the head and terminate in pull rings 34, 34'. Valve member 30 is maintained in its guiding passage 32 by means of a retaining 35 and adjusting screw boss 35 threaded in head 12 and having a central hole 36 through which the rod 33 passes.

Method of operation

40

This door closer of my invention is installed for use as follows: Base 5 is bolted or fastened to the header member of a door frame and anchor plate 27 is screwed or bolted to the top cross rail of the door. When the door is opened, the 45 pressure against lever 26 acts upon lever 9 forcing it, at its outer end 9a, to the right about the pivot at 23, thus causing end 21 to swing to the left. Lever 9, being secured to piston rod 16 by pin 22, draws the piston 15 on rod 16 to the left against 50 the compression of spring 18. In order that this stroke of piston 15 be insured of drawing sufficient air into the piston chamber to prevent a vacuum, I utilize the leather cup type of plunger common with many air pumps. Air is thus drawn 55

into the chamber around the leather piston cup, and this air, when put under pressure, forces the cup tightly against the piston wall to form a cushion.

- 5 Therefore, when the door is released by one opening it, spring 18 acts upon the piston rod 16 and piston 15 to close the door. The cushioned air in the piston chamber allows the door to close in proportion to the evacuation permitted by the 10 controllable escape port 29. If it is desired that the door close rapidly the valve member 30 is set to allow for the maximum escapement of air through port 29, and, of course, the degree of control may be varied by the size of the opening 15 presented by adjustment of valve 30 across port 29. It will be apparent that by closing valve 30 across port 29, the cushion of air in the piston will resist the force of spring 18 and the door will stand fully open until the air is released. 20 In order to simplify the installation of the valve member 30 I drill and tap an internally threaded hole into which boss 35 is screwed. As the member 30 butts against the lower end of the boss 35 a limitation of travel of the valve 30 is attained. Therefore, it being only necessary to either completely prevent the air escaping through port 29 or to have a partial opening, it will be seen that a pull on cord 33 opens the port to the maximum opening at which screw boss 35 30 is set, and a similar pull on cord 33' will close the port 29 entirely.

In the accompanying drawings and specifications I have illustrated and explained one complete example of the physical embodiment of my 35 invention, wherein the parts are combined and arranged according to one mode I have thus far

devised for the practical application of the principles of my invention, but it will be understood that changes and alterations may be made in this exemplified structure, within the scope of my appended claims, without departing from the 5 principles of my invention.

Having thus fully described my invention, what I claim as new and desire to secure by Letters Patent is:

1. The combination with a rigidly supported, 10 slotted, tubular housing having a transverse partition forming an air cylinder and a spring chamber, a piston in the air cylinder, a stem for the piston reciprocable in the partition and having a cup in the chamber, and a spring interposed be- 15 tween said cup and an end wall of the chamber, of an operating lever having a pivot exterior of the housing and pivoted at one end to the stem, a door-actuated lever pivoted at the other end of said operating lever, and means at the outer end 20 of the air cylinder for venting the same.

2. The combination with a rigidly supported, slotted, tubular housing having a transverse partition forming an air cylinder and a spring chamber, a piston in the air cylinder, a stem for the 25 piston reciprocable in the partition and having a cup in the chamber, and a spring interposed between the cup and an end wall of the chamber, of an operating lever having a pivot exterior of the housing, a slotted end for said operating 30 lever and means co-acting with said end for pivotal engagement with said lever, a door-actuated lever pivoted at the other end of said operating lever, and means at the outer end of the air cylinder for venting the same.

LESTER C. PERKINS.
